UNITED STATES PATENT OFFICE.

PAUL FEIG, OF NEW YORK, N. Y., ASSIGNOR, BY MESNE ASSIGNMENTS, TO NEW YORK STANDARD ASH CAN MANUFACTURING COMPANY, OF BROOKLYN, NEW YORK, A CORPORATION OF NEW YORK.

WEB-COATING MACHINE.

Application filed December 27, 1922. Serial No. 609,252.

To all whom it may concern:

Be it known that I, PAUL FEIG, a citizen of the United States, and resident of the borough of Manhattan, in the city and State of New York, have invented a new and useful Improvement in Web-Coating Machines, of which the following is a specification.

The object of my invention is to provide certain improvements in a machine for coating a traveling web whereby the supply of liquid to the distributor over which the web is drawn for the application of the liquid coating is automatically cut off and the machine is stopped when a predetermined length of web has been coated, a common manually operated means being employed for starting the machine and turning on the liquid supply to the distributor.

A practical embodiment of my invention is represented in the accompanying drawings, in which—

Fig. 1 represents in side elevation a machine for coating traveling webs with my improvements applied thereto.

Fig. 2 represents an enlarged detail top plan view of the liquid distributor.

Fig. 3 represents a cross section through the same.

Fig. 4 represents an enlarged detail view showing the means for imparting a step by step rotary movement to the control cams.

Fig. 5 represents an enlarged detail top plan of the portion of the machine which embodies my invention.

Fig. 6 represents a detail view partly in section of one of the control mechanisms.

Fig. 7 represents another detail view taken at right angles to Fig. 6 of one of the control mechanisms.

The machine in connection with which I have illustrated my invention is one for building hollow articles by wrapping the coated web around a suitable mandrel.

The web is denoted by 1 and it is fed around suitable rollers 2 from the supply roll 3 to the mandrel 4, which mandrel is suitably mounted on a shaft 5, driven from the cross shaft 6 by the gears 7, 8. This cross shaft 6 is driven from the main drive shaft 9 through the clutch 10, shaft 11, pulley 12, belt 13 and pulley 14.

The liquid distributor 15 is shown as a horizontally arranged tube provided in its

top wall with a series of holes 16 over which the web 1 is drawn. This distributor is supplied with the desired liquid, as for instance an adhesive from the supply pipe 17. A manually operated valve 18 is located in the horizontal portion of this supply pipe 17 for regulating and opening and closing the supply of liquid to the distributor. This horizontal branch of the supply pipe 17 is also provided with an automatically closing valve 19, the stem of which is provided with a lever 20.

The means which I have shown for automatically closing this valve 19 when a predetermined length of web has been drawn over the distributor and for stopping the machine at the same time, is constructed, arranged and operated as follows:—

A cross shaft 21 is driven continuously from the shaft 5 through a sprocket 22, chain 23 and sprocket 24. This shaft 21 is provided with an adjustable crank arm 25 which carries a hook arm 26, the free end of which is adapted to engage a toothed wheel 27 on the cam shaft 28 for imparting a step by step rotary movement to the said shaft 28. This shaft 28 is provided with two cams 29, 30, one for closing the valve 19 to shut off the liquid supplied to the distributor and the other for disconnecting the clutch 10 for stopping the machine.

The device for automatically closing the valve 19 comprises a two armed lever pivoted at 31, the upper arm 32 of which is connected by a flexible connection 33 to the valve lever 20. A spring 34 serves to tend to swing the arm 32 in a direction to close the valve 19. The lower arm 35 of this lever is engaged by a pin 36, carried by a vertically movable latch 37, the lower end of which latch is provided with a pin 38 arranged to be engaged by the cam 29 after a predetermined length of web has been fed, to depress the latch 37 against the tension of the spring 39, to release the pin 36 from its engagement with the arm 35 of the valve operating lever, to permit the lever to rock, to close the valve.

The mechanism for disconnecting the clutch 10 is quite similar to that disclosed with respect to the closing of the valve 19 except that in this instance the upper arm 40 of the rock lever is connected by a flexible connection 41 with a clutch operating lever

42. A spring 43 is provided, tending to disconnect the clutch when the arm 40 of the rock lever is released by its cam 30.

A common manually operated means is provided for opening the valve 19 and closing the clutch 10 for renewing the supply of liquid to the distributor and at the same time starting the machine, which manual means in the present instance is shown as 10 comprising a hand wheel 44, connected by flexible connections 45, 46 with the upper arms 32 and 40 of the two rock levers.

It is evident that various changes may be resorted to in the construction, form and 15 arrangement of the several parts without departing from the spirit and scope of my invention, hence I do not wish to be limited to the particular embodiment herein shown and described, but

20 What I claim is:—

1. A web coating machine including a liquid distributor, means for supplying liquid thereto, means operable to draw the web to be coated over the distributor, and 25 means for automatically cutting off the supply of liquid to the distributor when a predetermined length of web has been drawn over the distributor.

2. A web coating machine including a liquid distributor, means for supplying liquid thereto, means operable to draw the web to be coated over the distributor, and means for automatically stopping the machine and cutting off the supply of liquid 30 to the distributor when a predetermined length of web has been drawn over the distributor.

3. A web coating machine including a liquid distributor, means for supplying liquid thereto, means operable to draw the web to be coated over the distributor, means for automatically cutting off the supply of liquid to the distributor when a predetermined length of web has been drawn over 40 the distributor, and means for manually opening the supply of liquid to the distributor.

4. A web coating machine including a liquid distributor, means for supplying liquid thereto, means operable to draw the web to be coated over the distributor, means for automatically stopping the machine and cutting off the supply of liquid to the distributor when a predetermined length of web has been drawn over 50 the distributor, and a common means for manually starting the machine and opening the supply of liquid to the distributor.

5. A web coating machine including a liquid distributor, means for supplying liquid thereto, means operable to draw the web to be coated, over the distributor, a valve for controlling the supply of liquid to the distributor, and means for automatically closing said valve when a predetermined length of web has been drawn over the distributor.

6. A web coating machine including a liquid distributor, means for supplying liquid thereto, means operable to draw the web to be coated, over the distributor, a valve for controlling the supply of liquid to the distributor, and means for automatically stopping the machine and closing said valve when a predetermined length of web has been drawn over the distributor.

7. A web coating machine including a liquid distributor, means for supplying liquid thereto, means operable to draw the web to be coated, over the distributor, a valve for controlling the supply of liquid to the distributor, means for automatically closing said valve when a predetermined length of web has been drawn over the distributor, and means for manually opening said valve.

8. A web coating machine including a liquid distributor, means for supplying liquid thereto, means operable to draw the web to be coated, over the distributor, a valve for controlling the supply of liquid to the distributor, means for automatically stopping the machine and closing said valve when a predetermined length of web has been drawn over the distributor, and means for manually opening said valve.

9. A web coating machine including a liquid distributor, means for supplying liquid thereto, means operable to draw the web to be coated, over the distributor, a valve for controlling the supply of liquid to the distributor, and means for automatically stopping the machine and closing said valve when a predetermined length of web has been drawn over the distributor, and a common means for manually starting the machine and opening said valve.

10. A web coating machine including a liquid distributor, means for supplying liquid thereto, means operable to draw the web to be coated, over the distributor, a valve for controlling the supply of liquid to the distributor, and means for automatically closing said valve when a predetermined length of web has been drawn over the distributor, said means comprising a valve lever, a spring actuated lever connected to the valve lever, a cam operated by the web driving means, and a latch operated by the cam for controlling said spring actuated lever.

11. A web coating machine including a liquid distributor, means for supplying liquid thereto, means operable to draw the web to be coated, over the distributor, a valve for controlling the supply of liquid to the distributor, and means for automatically closing said valve when a predetermined length of web has been drawn over the distributor, said means comprising a valve lever, a spring actuated lever connected to the valve lever, a cam operated by the web driving means, a latch operated by the cam for controlling said spring actuated lever, and means connected to the valve lever for manually opening the valve.

12. A web coating machine including a liquid distributor, means for supplying liquid thereto, means operable to draw the web to be coated, over the distributor, a valve

for controlling the supply of liquid to the distributor, and means for automatically stopping the machine and closing said valve when a predetermined length of web has 5 been drawn over the distributor, said means comprising a clutch in the web driving means, a lever flexibly connected to said clutch, a valve lever, a spring actuated lever connected to the valve lever, cams operated 10 by the web driving means and latches operated by the cams for releasing the said clutch lever and said spring actuated lever.

12. A web coating machine including a liquid distributor, means for supplying liquid thereto, means operable to draw the web to be coated, over the distributor, a valve for controlling the supply of liquid to the distributor, means for automatically

stopping the machine and closing said valve when a predetermined length of web has 20 been drawn over the distributor, said means comprising a clutch in the web driving means, a lever flexibly connected to said clutch, a valve lever, a spring actuated lever connected to the valve lever, cams operated 25 by the web driving means and latches operated by the cams for releasing the said clutch lever and said spring actuated lever, and means connected to the clutch lever and valve lever for manually closing the clutch 30 and opening the valve.

In testimony that I claim the foregoing as my invention, I have signed my name this 11th day of December, 1922.

PAUL FEIG.
